ARCHER'S AID

Marvin F. Pursley, Box 465, Ravenswood, W. Va.

Filed Nov. 5, 1958, Ser. No. 772,028

1 Claim. (Cl. 124—35)

This invention relates to archery, and in particular a bow having a pistol grip connected by a telescoping rod to the intermediate part with latching means in the rod and with means for holding the bow string in a cocked position whereby the string may be released by a trigger.

The purpose of this invention is to provide means for retaining the bow string in a retracted position to facilitate aiming an arrow at a target.

Various types of devices have been provided for holding arrows in position for projection, however, such devices are relatively clumsy and it is difficult to aim an arrow accurately thereby. With this thought in mind this invention contemplates a relatively small telescoping rod secured to one side of the bow with latching means in telescoping sections of the rod and with the bow string held in a notched disc rotatably mounted in an extended end of a rod whereby the disc may be actuated to release the bow string by a trigger.

The object of this invention is, therefore, to provide a supporting device in combination with a bow to facilitate retaining and releasing the bow string so that accurate shooting may be obtained.

Another object of the invention is to provide a telescoping rod member for use on a bow to facilitate projecting an arrow by the bow in which the device may be secured upon the conventional bow.

Another important object of the invention is to provide a telescoping strut for use on a bow to facilitate holding the bow string and arrow in cocked position in which the device is of comparatively light weight.

A further object of the invention is to provide a telescoping rod designed to be mounted on the side of a bow with a pistol grip at the extended end and with a notched disc for holding the bow string rotatably mounted in the rod and actuated to release the bow string by a trigger, in which the device is of a simple and economical construction.

With these and other objects and advantages in view the invention embodies a tube having a clamp on one end for mounting the tube on the side of a bow, a telescoping tube slidably mounted in the former rod and having a latch therein for retaining the telescoping rod in extended position, a pistol grip on the extended end of the telescoping rod, and a notched disc rotatably mounted in the rod and actuated to release the bow string which may be trained therethrough by drawing a trigger of the device rearwardly.

Other features and advantages of the invention will appear from the following description taken in connection with the drawing, wherein:

Figure 1 is a side elevational view illustrating the improved pair of telescoping members with the pistol grip on one end of the members and with opposite end of the members secured by a clamp to the intermediate portion of the bow.

Figure 2 is a side elevational view of the telescoping members with the parts shown on an enlarged scale and

with parts broken away and the remaining parts shown in section.

Figure 3 is a sectional plan taken on line 3—3 of Figure 1 showing the inner portion of the telescoping rod and illustrating, in particular, the arrangement of the notched disc for holding the bow string.

Figure 4 is a perspective view with the parts in exploded positions and shown on an enlarged scale showing, in particular, the notched disc and trigger actuated pin for holding and releasing the disc.

Figure 5 is a cross section taken on line 5—5 of Figure 2 showing the position of the telescoping tube members on the side of a bow.

Referring now to the drawing wherein like reference characters denote corresponding parts the bow attachment of this invention includes a tube 10, a telescoping rod 11 slidably mounted in the tube, a disc 12 rotatably mounted in a bore 13 of the rod 11 and having notches 14 in the peripheral surface, a rod 15 slidably mounted in the bore 13 having a trigger 16 pivotally mounted therein by a pin 17 and having a pin 18 extended from one end and positioned to nest in one of the notches 14 of the disc 12, a spring 19 also mounted in the bore 13 and positioned to urge the rod 15 toward the disc 12, a cap 20 threaded on the rear end of the rod 11, a grip 21 extended from one side of the rod 11, and a clamp 22 for attaching the tube 10 to one side of a bow 23.

The clamp 22 is formed with a bar 24 that is mounted on the bow by screws 25 and the upper portion of the bar is rolled over around the tube 10 and positioned with the extended end 26 urged against the bar 24 by a thumb nut 27 on a stub 28 extended from the bar.

Any well-known conventional means may be provided on the rod 11 and tube 10 for limiting the outward movement of the rod 11 to prevent the rod 11 from pulling out of the tube 10, and as illustrated in Figure 2, the rod 11 is provided with a latch 30 that is positioned in a recess 31 in the rod and the latch is pivotally mounted by a pin 32 and urged outwardly by a spring 33 also positioned in the recess 31. The lower end of the spring extends into a notch 34 in the rod to provide means for retaining the spring in position. When it is desired to collapse the device the latch 30 is pressed inwardly so that the latch slides on the inner surface of the tube 10.

The disc 12, in which the notches 14 are positioned is rotatably mounted on a pin 35 extended through the rod 11 and, as shown in Figure 2, the ends of the pin are riveted over forming heads 36 which retain the pin in position.

The trigger 16 is positioned in a recess 37 in the rod 15 and, as shown in Figure 2, the trigger extends through an elongated slot 38 which permits the trigger to be drawn rearwardly a sufficient distance to permit the pin 18 to be withdrawn from one of the notches 14 when it is desired to release the bow string. The device is provided with a trigger guard 39 which extends from the grip 21 to the lower side of the rod 11.

The parts may be removed by removing the cap 20 which is threaded on the end of the rod 11.

With the parts assembled as illustrated and described the tube 10 is secured by the clamp 22 to one side of the bow 23 and with an arrow 40 in position the bow string 41 is placed in one of the notches 14 and the rod 11 withdrawn until the latch 30 snaps upwardly to the position shown in Figure 2 whereby the telescoping device is retained in an extended position.

To project the arrow the trigger 16 is drawn rearwardly until the pin 18 leaves one of the notches 14 at which time the bow string snaps the disc 12 around so that the string is released and the arrow projected.

The attachment may readily be mounted on the side

of a conventional bow and by releasing the latch 30 the parts are collapsed for storage and shipment. The attachment may also be removed from a bow by removing the screws 25 which extend through the base or bar 24 of the clamp.

The bow string 41 may be wrapped with dental floss 42, or the like at the point where the bow string engages the arrow to frictionally retain the arrow in position and prevent the arrow accidentally dropping from the bow when the arrow is released, by the fingers of the archer.

It will be understood that modifications, within the scope of the appended claim, may be made in the design and arrangement of the parts without departing from the spirit of the invention.

What is claimed is:

In an attachment for a bow, the combination which comprises a tube, a clamp for mounting the tube on the side of a bow, a telescoping rod having a recess therein adjacent one end thereof slidably mounted in the tube, a latch mounted in the recess in the rod and engaging the end of the tube for retaining the rod in an extended position in relation to the tube, said

rod having an open ended longitudinally extending bore in the other end thereof, a horizontally disposed notched disc rotatably mounted in the bore in the rod and positioned whereby one of the notches receives the bow string, a trigger actuated rod slidably mounted in the bore in the telescoping rod outwardly of the notched disc and having a pin on one end thereof positioned to extend into one of the notches of the notched disc, resilient means positioned in the bore in the telescoping rod and having one end thereof engaging the other end of the trigger actuated rod for urging the pin into one of the notches of the notched disc, and a cap threaded on the open end of the telescoping rod and engaging the other end of the resilient means for retaining the parts in operative position.
